US00D899503S

(12) **United States Design Patent** (10) Patent No.: **US D899,503 S**
Boinnard et al. (45) Date of Patent: **** Oct. 20, 2020**

(54) **SUNGGLASSES**

- (71) Applicant: **100% SPEEDLAB, LLC**, San Diego, CA (US)
- (72) Inventors: **Ludovic Francis Boinnard**, San Diego, CA (US); **Marc Guy Blanchard**, Solano Beach, CA (US); **Jerome Jacques Marie Mage**, Los Angeles, CA (US)
- (73) Assignee: **100% SPEEDLAB, LLC**, San Diego, CA (US)
- (**) Term: **15 Years**
- (21) Appl. No.: **29/673,210**
- (22) Filed: **Dec. 12, 2018**

Related U.S. Application Data

- (63) Continuation-in-part of application No. 29/672,927, filed on Dec. 10, 2018, now Pat. No. Des. 870,789, and a continuation-in-part of application No. 29/662,083, filed on Aug. 31, 2018, now Pat. No. Des. 878,454, said application No. 29/672,927 is a continuation of application No. 29/605,269, filed on May 24, 2017, now Pat. No. Des. 855,096, which is a continuation of application No. 14/548,217, filed on Nov. 19, 2014, which is a continuation-in-part of application No. 13/750,093, filed on Jan. 25, 2013, and a continuation-in-part of application No. 29/501,895, filed on Sep. 9, 2014, now Pat. No. Des. 727,400.

(57) **CLAIM**

The ornamental design for sunglasses, as shown and described.

DESCRIPTION

FIG. 1 is a front, top, left perspective view of sunglasses showing the new design;

FIG. 2 is a rear, bottom, right perspective view thereof;

FIG. 3 is a front side elevational view thereof;

FIG. 4 is a rear side elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines illustrate portions of the sunglasses and form no part of the claimed design.

1 Claim, 6 Drawing Sheets
